W. P. WALTER,
APPARATUS FOR ADMINISTERING ANESTHETICS,
APPLICATION FILED JUNE 19, 1915.

1,211,647.

Patented Jan. 9, 1917.

UNITED STATES PATENT OFFICE.

WILL P. WALTER, OF CHICAGO, ILLINOIS.

APPARATUS FOR ADMINISTERING ANESTHETICS.

1,211,647.

Specification of Letters Patent. Patented Jan. 9, 1917.

Application filed June 19, 1915. Serial No. 34,980.

To all whom it may concern:

Be it known that I, WILL P. WALTER, a citizen of the United States, and a resident of Chicago, in the county of Cook and State 5 of Illinois, have invented certain new and useful Improvements in Apparatus for Administering Anesthetics; and I do hereby declare that the following is a full, clear, and exact description thereof, reference being had to the accompanying drawings, and to the letters of reference marked thereon, which form a part of this specification.

This invention relates to improvements in apparatus for administering anesthetics and analgesics and consists of the matters 15 hereinafter described and more particularly pointed out in the appended claims.

The invention is herein illustrated as applied to an apparatus of the kind disclosed in an application for patent filed by me on April 3d, 1915 and bearing Serial Number 18,868. In general, the apparatus disclosed therein comprises a head adapted for attachment to a pair of gas cylinders (one containing nitrous oxid and the other oxygen), said head including washing tubes, one associated with each gas cylinder, an ether tube and a heater casing, and a vertically adjustable standard, by means of which said head 20 may be brought into proper relation with respect to the said gas cylinders. Conduits are provided connecting each gas cylinder with its associated washing tube, connecting each washing tube with the ether tube, 25 connecting each washing tube with the heater casing and connecting the ether tube with heater casing. Shut-off valves are used in all conduits excepting those leading from the gas cylinders to their associated washing tubes, so that the gases may be caused 30 to pass either directly from the washing tubes to the heating chamber or from the washing tubes, through the ether tube, to the heating chamber. Said valves require 35 very strict attention to see that when one path for the gas is open, the other is closed, and this is of particular annoyance when the requirement for changing the path occurs during an operation and when ether 40 is either to be added to or omitted from the anesthetic fluid. A failure to close the one valve when the other is opened, may result in accidents of serious consequence to either the operator or to the patient and the gravity 45 of the possible results are increased by

reason of the nearness of the apparatus to both operator and patient.

It is the object of the present invention to overcome the defects in and the objections to the valve system previously mentioned 60 and to provide in place thereof a system of conduits and valves which will eliminate the possibility of error and obviate the dangerous results and make the apparatus such that no matter how the attention of the 65 operator may be absorbed, no harmful results may occur by his hasty manipulation of any of the valves.

In the drawings:—Figure 1 is a top plan view of an apparatus for administering 70 anesthetics and analgesics embodying my invention. Fig. 2 is a view representing a vertical section through Fig. 1 in a plane indicated by the line 2—2 of Fig. 1. Fig. 3 is a view representing on an enlarged 75 scale a vertical section through a valve mechanism embodied in the present invention, the plane of the section being indicated by line 3—3 of Fig. 1. Fig. 4 is a view representing a horizontal section through 80 the valve illustrated in Fig. 3, the plane of the section being indicated by line 4—4 of Fig. 2. Fig. 5 is a top plan view of said valve.

Referring now to that embodiment of my 85 invention illustrated in the accompanying drawings and more particularly to Figs. 1 and 2:—10 indicates as a whole the head or yoke of the apparatus which is attached to the necks of the gas cylinders 11 and 12, 90 the one containing usually nitrous oxid and the other oxygen. Said head is supported in the case of the apparatus described in the application hereinbefore referred to by an adjustable standard, not shown in full 95 but the upper ends of which are indicated at 10^a, 10^b.

The head 10 comprises a rectangular frame 14, three metallic caps 15, 16 and 17, respectively, a casing 18, containing a heating chamber and the several conduit, or pipe connections which will be more specifically referred to later.

The frame 14 is provided at its ends with rectangular openings 14^a, 14^b, which are 105 adapted to receive the squared necks 11^a, 12^a on the top of the respective gas cylinders, and suitable means are arranged to secure said frame thereto.

The end caps 15 and 17 respectively pro-

vide support and closure for the tops of glass tubes or reservoirs 15^a, and 17^a, which contain a washing fluid, usually water, and the intermediate cap 16 provides a support and closure for a third glass tube or reservoir 16^a in which is contained ether. As in the apparatus described in the before mentioned application for patent, all of said tubes or reservoirs are closed at their bottom ends in the manner of the familiar test tubes. Said tubes are detachably connected to their respective caps.

Each cap (15 and 17) for the washing tubes has a passageway 20 extending transversely through it and opening at one end through the peripheral edge and at the other end through the bottom of the cap at its center where it has a vertical metal tube 21 threaded into it. The end of the passageway 20 opening through the peripheral edge of the cap has threaded into it a pipe 22, the other end of which is secured to the frame 14 and extends a short distance beyond and into one of the rectangular openings at the end of said frame where it is adapted for a gas tight connection within the discharge vent formed in the squared neck of the gas cylinder for the passage of the gas. The neck of said gas cylinder is held rigidly engaged with the end of each of the pipes 22 by means of a clamping screw 22^a, which is threaded through the back of the frame 14 in line with the pipe 22 so as to engage said neck opposite its discharge vent. Each cap 15 and 17 is provided with a second passageway 23, 23, arranged, as shown, at right angles to the passageways 20. Said passageways 23 open at one end through the bottom of the cap and at the other end through the peripheral edge of the cap in line with a diametrically extending passageway 24 formed in the cap 16 of the ether tube. The passageway 24 opens at its ends through the edge of the cap and at a point intermediate its ends (preferably at the center of said cap) through the bottom thereof where it has threaded into it an aspirator tube 25.

The cap 16 of the ether tube is provided with a passageway 26 which extends, as shown, at right angles to the passageway 24. Said passageway 26 opens at one end through the bottom of the cap 16 and at its opposite end through the peripheral edge of the cap where it has threaded into it a pipe 27 which leads to and is connected with the heater casing 18. The passageways 23 in the caps 15 and 17 respectively and the diametric passageway 24 in the cap 16 are connected by valve casings 30 with apertured extensions 31, 31, threaded into said passageways.

Each valve casing 30 has a vertically tapered bore 32 (the outside of said casing

being correspondingly tapered) in which is provided a rotative valve plug 33 which is tapered to fit the bore 32. Each valve plug is provided with an axially arranged stem 34 which depends below the bottom of the casing and which extends through a washer 35 engaging with the bottom of said valve casing. The bottom end of said stem is threaded to receive a nut and washer 36 and a coiled spring 37 is interposed between the washers 35 and 36, the spring surrounding the stem. This construction holds the valve plug 33 in proper seating relation with the tapered bore of the valve casing and permits the regulation of the tension on said plug so that a gas tight joint may be had. In approximately the same horizontal plane as that of the apertures in the extension 31 of the casing, there is provided in each valve plug 33 a diametrically arranged port 39 and a second port 40 arranged at an angle thereto. The port 40 is located to one side of but in the same plane as the port 39.

Each valve casing is provided with a tubular extension 41 arranged at an angle to the diametric line of the extension 31, 31 of said valve casing. The extension 41 is provided with an aperture 42 in the same plane as that of the apertures in the extension 31 and said aperture opens at one end into the bore 32 in the valve casing and is enlarged at its opposite end to receive the threaded end of a conduit or pipe 43 which leads to and is connected with the heater casing 18. Union fittings are preferably interposed in each conduit 43, 43 and 27 leading to the heater casing for ease in assembling.

The upper end of the valve plug 33 is provided with suitable means for hand operation. As illustrated, a knurled disk is fixed to the top of the valve plug.

It is apparent from the foregoing description that by rotating either of the valve plugs 33, the ports 39 may be caused to register with the apertures in the tubular extensions 31 as is illustrated in Fig. 4. In use of the apparatus with the ports so registering, a free passage of the gases is provided for, from the gas cylinders to the ether tube, (the same having passed through the washing tubes), after which the said gases may, after having absorbed or taken up enough vaporized ether therein, pass into the heating chamber 18 through the conduit 27, from which they will be delivered at the proper temperature to the breathing bag. (Not shown.) Should it be desired that no ether be mixed with the gas being administered, the valve plugs 33, either or both, may be rotated in a reverse direction and the port or ports 40 in the valve plugs 33 will then be brought to register with the passageways 23 in the caps 15 and 17 re-

spectively and with the apertures 42 in the tubular extension 41 of each valve casing so that the gases after having passed through the washing tubes, will be delivered respectively into the pipes 43 from which they will pass into the heating chamber 18. The orifices of the ports 39 and 40 are so positioned in the valve plug 33 that when said plug is rotated to bring one or the other of said ports into communication with the ports in the valve casing, one of said valve plug ports, as for example, the port 39, will be in communication therewith before the other port (40) is out of communication with said casing port and vice versa. This relative position of said port orifices is clearly illustrated by dotted line in Fig. 4 and is advantageous in that a pressure cannot build up in either of the washing tubes to produce a breakage of the same when its associated valve plug is rotated for the purpose before mentioned. From the heating chamber the mixed and properly temperatured gases are conducted to the breathing bag and are administered to the patient in the manner described in the application referred to.

The valve plug 33 is provided with a stop member, which as shown, is a screw 51 depending through the radial flange 45 at the top of the plug that provides its handle part. Said screw projects below the flanged top of the plug and coats with oppositely facing shoulders 50, one of which is so located that when the screw 51 is engaged with it, the port 40 is in register with the conduits associated with it, whereas when said screw is engaged against the other shoulder, the port 39 is in register with the conduits that it is associated with. Thus when the valve plug is moved as far as it can be in one direction, the washing tubes are connected with the ether tube and at the same time automatically disconnected from the direct connection with the heating chamber, being connected with said heating chamber only through said ether tube and when said valve plug is engaged with the other stop shoulder, said washing tube is connected directly with the heating chamber and disconnected from the ether tube. The danger of accidents is thus entirely eliminated and the apparatus in a measure is made fool-proof in that it is impossible by lack of attention or otherwise to connect the washing tubes to the heating chamber by both of the associaed conduits and passages at the same time.

The advantages of my improvement will

be apparent to those familiar with the operation of an apparatus of this kind, wherein the attention of the operator is necessarily so concentrated upon the patient and the effect of the anesthetic or analgesic fluid upon the face of the patient's physical condition and where the change of the mixture of fluid administered, if made at all, must be done quickly and with as little distraction of the attention of the operator as possible.

While in describing the invention, I have referred to certain details of mechanical construction and arrangement, it is to be understood that the invention is in no way limited thereto except as may be pointed out in the appended claims.

I claim as my invention:—

1. In an apparatus of the kind described, a gas cylinder, a washing tube, an ether tube, a heating and mixing chamber, means directly connecting said washing tube with said ether tube, said means including a valve casing, means providing a by-pass connecting said valve casing with said heating chamber, and a valve provided with two ports, one port being adapted for connecting the washing tube with said by-pass, and the other port being adapted to connect the washing tube with the ether tube, said ports being constructed so that when one is in register with its associated conduit, the other is closed.

2. In an apparatus of the kind described, a gas cylinder, a washing tube, an ether tube, a heating and mixing chamber, means directly connecting said washing tube with said ether tube, said means including a valve casing, means providing a by-pass connecting said valve casing with said heating chamber, a valve provided with two ports, one port being adapted for connecting the washing tube with said by-pass, and the other port being adapted to connect the washing tube with the ether tube, said ports being constructed so that when one is in register with its associated conduit the other is closed, and stop means to limit the movement of said valve in either of its two positions.

In testimony, that I claim the foregoing as my invention I affix my signature in the presence of two witnesses, this 11th day of June A. D. 1915.

WILL P. WALTER.
